US00D626812S

(12) **United States Design Patent**
Macsay et al.

(10) **Patent No.:** **US D626,812 S**
(45) **Date of Patent:** **** Nov. 9, 2010**

(54) **PIPE CUTTER**

(75) Inventors: **Steven M. Macsay**, Strongsville, OH (US); **Glen R. Chartier**, Avon Lake, OH (US)

(73) Assignee: **Emerson Electric Co.**, St. Louis, MO (US)

(**) Term: **14 Years**

(21) Appl. No.: **29/353,709**

(22) Filed: **Jan. 13, 2010**

(51) **LOC (9) Cl.** **08-03**

(52) **U.S. Cl.** **D8/60**

(58) **Field of Classification Search** D8/1, D8/4, 5, 14, 20, 51-56, 58, 105-107, 98, D8/99; D27/195; 30/92-97, 101, 102

See application file for complete search history.

(57) **CLAIM**

The ornamental design for a pipe cutter, as shown and described.

DESCRIPTION

FIG. 1 is a front left perspective view of a pipe cutter.

FIG. 2 is a left side view of the pipe cutter of FIG. 1.

FIG. 3 is a right side view of the pipe cutter of FIG. 1.

FIG. 4 is a rear elevational view of the pipe cutter of FIG. 1.

FIG. 5 is a front elevational view of the pipe cutter of FIG. 1.

FIG. 6 is a top plan view of the pipe cutter of FIG. 1; and,

FIG. 7 is a bottom plan view of the pipe cutter of FIG. 1.

The dash lines in FIGS. 1-4 and 7 are for illustrative purposes only showing environmental subject matter and form no part of the claimed designs.

1 Claim, 7 Drawing Sheets
